UNITED STATES PATENT OFFICE.

DANIEL J. McCARTHY, OF ELGIN, ILLINOIS, ASSIGNOR TO CHICAGO RAILWAY SIGNAL AND SUPPLY COMPANY, A CORPORATION OF ILLINOIS.

CHROMATIC LIGHT SIGNAL SYSTEM.

Application filed October 11, 1920. Serial No. 416,047.

To all whom it may concern:

Be it known that I, DANIEL J. McCARTHY, a citizen of the United States, residing at Elgin, in the county of Kane and State of Illinois, have invented certain new and useful Improvements in Chromatic Light Signal Systems, of which the following is a specification.

This invention relates to improvements in chromatic light signal systems.

One of the objects of the present invention is to increase the reliability, effectiveness and integrity of such systems and to simplify and cheapen the cost of production or devices of this character, wherein one lens or lens combination serves for a plurality of characteristically different indications, retaining the advantages and benefits resulting from the use of the more expensive and involved apparatus.

Another object of the invention is the provision of means by use of which false reflected signals can not be indicated from a signal lamp, lens or reflector not actively in the signalling condition. In separate unit signal systems, as heretofore used, false signals are frequently exhibited when the light rays from a powerful headlight of an approaching locomotive is projected into them. This is due to the reflection of the rays from the bulb of the incandescent lamp of the signal unit, notwithstanding the fact that the lamp thereof may, at the time, be de-energized or not alight. Parallel rays from the head light entering the lens will be concentrated at the exposed focal point and be reflected from the surface of the glass of the bulb. These rays leave the unit, or lens system of the signal, and produce the same visual effect as if they had originated at the focal point of the signal light and to an observer they show the same effect that the energized lamp of the signal produces.

Another object of the invention is to overcome this glaring deficiency and dangerous feature of signal systems by shutting off or shielding the inactive lamps of the "safety" and "caution" signals from an observer, by the interposition of an opaque screen when the lamps are not actively energized. If a false danger signal be sent from the danger lens and lamp it is not a matter of such a great importance.

Another object is the provision of auto-

matic means for interposing an opaque screen between the "safety" lamp, the "caution" lamp and an observer, when said lamps are de-energized, exposing only the "danger" lamp behind the lens combination. 60

Another object is the provision of a reflector, having an opaque backing forming a screen, one for the "safety" lamp and one for the "caution" lamp, and means to move each reflector into its reflecting position, 65 between its lamp and the lens combination, by the same electric current that lights the energized lamp and which moves out of its reflecting position and interposes the screen before the associated lamp by effect of 70 gravity, when its lamp is de-energized or extinguished.

Other, further and more specific objects of the invention will become readily apparent to persons skilled in the art, from a 75 consideration of the following description, when taken in conjunction with the drawings, wherein:—

Figs. 1, 2 and 3 are diagrammatic views showing the positions of the parts under 80 the various conditions of operation.

In Fig. 1 the parts are in position to project thru a common lens a green light indicative of "clear" or "safety."

In Fig. 2 the parts are in position to project thru the same lens a red light indicative of "danger." The parts in this view show the positions which they assume, by effect of gravity, when the "caution" and "safety" lamps are de-energized from any 85 cause.

Fig. 3 shows the positions of the parts when the yellow or "caution" light is being projected thru the lens.

The reflector shown in Fig. 1 completely 90 cuts off the light from lamp 6 at R and it interposes an opaque shield between the reflector of the caution lamp and lamp 7 so that neither the lamps R nor Y can, under any circumstances of operation, project 100 their lights thru the lens 5, while the reflector of the safety lamp is in the position shown.

The same condition of operation is shown in Fig. 3 in which the reflector designed to 105 reflect the yellow light thru the lens is in reflecting position.

In this diagrammatic arrangement, chosen to exemplify the invention, the lens combination 5 may be a single lens or a combina- 110

tion of lenses having a focal point at 6. A side light 7, which for example may be green, indicative of the fact that the tracks are clear, or a safety signal, is arranged with respect to its particular reflector to pass light thru the lens 5 at suitable times, while the reflector of light 8, which may be of yellow cast, is arranged in the same manner and for the same purpose on the opposite side of the light proceeding from the lamp R.

Reflector 9 is, preferably, in the form of a mirror, having a backing 9' which is opaque, the reflecting and screening structure being hinged at 10 and controlled by the solenoid 11, which is in series with the lamp 7.

A counterweight 12 normally holds the reflecting mirror 9 in position shown in Figs. 2 and 3 and out of the path of the light proceeding from the lamp 6 or red light R.

13 is a mirror reflector having an opaque back 13' and in every respect is a duplicate of the mirror structure 9. It is controlled by the solenoid 14 which is in series with the lamp 8. The mirror is pivoted as at 15 and is provided with a short arm 16 which is pivoted at 18 to the rod 19.

Instead of the lamps 6, 7 and 8 being of different colors, they may be each provided with a colored glass plate, such as a green plate 20, a red plate 21 and a yellow plate 22. The same apparatus is shown in Figs. 1, 2 and 3 with the parts in somewhat relatively different positions for accomplishing the various results, desired to be effected by the use of the signal system.

It is manifest that the signal system can be controlled by any of the well known auxiliary means or methods now employed in any of the block signal systems. The system herein disclosed shows that which is commonly known as the polarized system in which a polarized relay is employed for reversing direction of current thru part of the conducting apparatus. The track circuit C is energized by the battery B thru the contacts of the track relay 25 and the track circuit C' is energized by the battery B'.

26 is a polarized relay controlled from the track circuit C and when the train T enters track section C the relay armature moves to the position in Fig 2, which position causes current to flow from the battery 27 to the red lamp R, thus giving the red indication or danger signal by the light therefrom passing directly thru the lens 5. When the train T leaves the track section C and enters the track section C', the relay 25 is shunted so that its contacts cause a reversal of current in the track section C from the battery B, which causes the relay 26 to assume the position shown in Fig. 3 and allows the energizing of the lamp 8 at Y and the coil 14. This gives the caution or

yellow indication because the solenoid 14 being thus energized by the same current that lights the lamp 8 the core 14' of the solenoid is attracted into the solenoid, as more clearly shown in Fig. 3 and the reflecting mirror 13 is raised into position shown. Therefore the light from the lamp 8 is projected against the surface of the mirror and from thence reflected thru the lens 5. When the mirrors are in oblique positions the red light is screened from the lens.

When the train T passes out of the track section C' relay 25 is again energized, its contacts causing reversal of the current in the track section C, which causes the relay 26 to assume a position to energize the lamp 7, or the green lamp, and the coil 11, thus giving a green or "clear" indication in the same manner.

It will now be apparent that should any one of the lamps, lamp 7 or lamp 8, burn out or the circuit be opened by other cause, the respective reflector, operated by the coil connected in series therewith, will not be thrown across the beam of light from the red lamp 6 and therefore the path of light from the red lamp will not be obscured.

While I have herein shown a single embodiment of my invention, for the purpose of clear disclosure, it will be manifest, to persons skilled in the art, that many changes may be made in the general arrangement and configuration of the parts within the scope of the appended claims.

Having described my invention what I claim as new and desire to secure by Letters Patent is:—

1. In a railway signal system the combination of a plurality of fixed sources of different colored lights; an opaque reflector structure, normally in the path of light from one source of light and remotely controlled means to move the reflecting structure into position to reflect light from said source and shut off light from the other sources.

2. In a railway signal system the combination of a plurality of sources of different colored lights; a lens thru which light is directly projected from one source of light; an opaque reflector structure normally in the direct path of light from another source of light and remotely controlled means to move the reflector structure to position to reflect light thru the lens from the second mentioned source of light and to shut off light of the first source of light from the lens.

3. In a railway signal system the combination of a red light, indicative of danger, and a green light indicative of safety; a lens thru which the light from both sources is alternately projected; an opaque reflector structure normally maintained out of the path of the light, of the danger light, and in the path of light of safety light by effect

of gravity, and remotely controlled means to move said structure into the path of light of the danger light and into position to reflect light, thru the lens, from the safety light.

4. In a railway signal system the combination of a red light, indicative of danger; a green light indicative of safety, and a yellow light indicative of caution; a lens thru which the red light directly projects; reflecting means one normally in the path of the green light and one normally in the path of the yellow light to shut off light therefrom selectively and remotely controlled means one for each light reflecting means to move said light reflecting means to reflect light from the green light or from the yellow light, thru said lens and to shut off light from the red light.

5. In a railway signal system, a red light indicative of danger; a lens in the path of the light therefrom; an opaque reflector on each side of said path of light, normally maintained out of said path by effect of gravity; a green side light, normally behind one reflector and a yellow side light behind the other reflector and a means, one for each reflector, to alternatively move the respective reflector into the path of light from the red light and into position to reflect light thru the lens from one of said side lights.

6. In a railway signal system a lens; a red light projecting a path of light directly thru the lens; a plurality of reflecting mirrors, each mirror having an opaque backing and each pivoted to one side of said path of light held out of said path by effect of gravity; a side light normally behind each mirror and means, one for each mirror to move its associated mirror across said path of light and into the field of its associated side light to project light therefrom thru said lens and to shut off the light from the red light.

7. In a railway signal system, a lens; a red light projecting a path of light thru the lens; two spaced apart reflectors, one on

each side of said path of light, held out of the path by effect of gravity; a solenoid for each reflector, when energized to move the respective reflector across said light path and a source of light for each reflector arranged, with respect to its reflector, to cause the latter to reflect light thru the lens from its moved position.

8. In a railway signal system a lens; a fixed red light arranged to project its rays directly thru the lens; a plurality of fixed side lights; a reflector for each side light, and remotely controlled means for each reflector to move the latter into position intercepting the red light and adapted to reflect the rays thru the lens from a side light.

9. In a railway signal system the method of alternately projecting a plurality of distinctive lights thru a common lens which consists in shielding the light from one fixed source and reflecting the light from another fixed source then shielding the light from the last mentioned source and permitting the light from the first mentioned source to pass thru the lens.

10. In a railway signal system the method of alternately projecting a plurality of distinctive lights from fixed sources thru a common lens, one light of which is red, which consists in normally permitting the red light to pass thru the lens, then interposing a shield between the lens and red light and reflecting another light thru the lens, then removing the shield.

11. In a railway signal system the method of alternately projecting a plurality of distinctive lights into a common field which consists in shielding the light from one fixed source and reflecting the light from another fixed source into said field, then shielding the light of the last mentioned source from said field and permitting the light from the first mentioned source to pass into said field.

In testimony whereof I hereunto subscribed my name.

DANIEL J. McCARTHY.
